UNITED STATES PATENT OFFICE.

SAMUEL L. ALLEN, OF MOORESTOWN, NEW JERSEY.

CULTIVATOR.

1,008,445.

Specification of Letters Patent. Patented Nov. 14, 1911.

Application filed January 9, 1908. Serial No. 409,935.

To all whom it may concern:

Be it known that I, SAMUEL L. ALLEN, a citizen of the United States, and a resident of Moorestown, county of Burlington, State of New Jersey, have invented certain new and useful Improvements in Cultivators, of which the following is a full, clear, and exact description, reference being had to the accompanying drawings, forming a part of this specification.

My invention relates to improvements in cultivators and more particularly to riding cultivators which are adapted to work a number of rows at a time.

The main objects of my invention are to increase the efficiency of a cultivator of this class and to lessen the labor required in its operation.

More specifically stated the main objects of my invention are to provide in a cultivator improved steering mechanism; an improved means for adjusting and clamping the cultivator blades in position; improved means for balancing the tongue of the cultivator and for raising the cultivator blades; and other improvements, all of which will be more fully set forth in the following description and claims.

In the accompanying drawings, Figure 1 is a side elevation of a cultivator constructed in accordance with this invention; Fig. 2 a top plan view of the same; Fig. 3 a fragmentary perspective view of one of the wheels and its support, and part of the steering gear; Fig. 4 a fragmentary side elevation of part of the steering gear, showing the steering means and the foot rest; Fig. 5 a plan view of the portion shown in Fig. 4; Fig. 6 a fragmentary side elevation showing the inner side of the tongue and its supporting means; Fig. 7 a fragmentary rear elevation of the tool bars and tools carried thereby; Fig. 8 a top plan view of one of the tool clamps in position upon the tool bar; Figs. 9, 10 and 11 are transverse sections on the lines 9—9, 10—10 and 11—11 respectively of Fig. 7.

Referring to the drawings, one embodiment of this invention comprises a substantially rectangular main supporting frame 1 extending substantially the full width of the machine and having a transverse tubular member 2 forming the rear side thereof and projecting over the supporting wheels 3 which are carried thereby.

The side wheels 3 are supported upon L-

shaped axles 4 which are pivotally mounted in the vertical standards 5. The upper ends of the standards 5 form split sleeves 6 which are slidably mounted upon the said transverse tubular member 2 of the main supporting frame and are held in any desired position thereon by means of bolts 7 passing through the standards to bind the parts of the sleeves together. Each axle 4 has a bracket 8 rigidly secured thereto and carrying a crank arm 9 and also a bar 10 extending over the edge of the wheel to form a scraper. The said crank arms of the wheel axles are pivotally connected together by means of a pair of links 11, which are provided at their ends with a series of holes 12 spaced longitudinally of the links and adapted to receive the pivot bolts 13 whereby the ends of the crank arms may be connected at various points to the links.

Each wheel standard is provided at its lower end with a brace 14, connected at one end to the standard by means of the bolt 15 and at its other end to the forward transverse member of the main supporting frame by means of the bolt 16, the said member of the frame being provided with holes 17 spaced longitudinally of the member whereby the outer end of the said brace may be connected at various points to the frame.

The adjustment of the wheels transversely of the machine to correspond to various widths between rows is accomplished by disconnecting the free ends of the axle 80 crank arms from their links, and the outer ends of the standard braces from the frame, and loosening and sliding the wheel standards upon their tubular support to bring the wheels into the desired positions, after 90 which the standards are tightened and the crank arms and braces are correspondingly connected to the links and frame respectively.

The draft member of the cultivator is, in this instance, a tongue 18, which is pivoted at its inner end, by means of a bolt 19 between a pair of braces 20, the ends of the braces being flanged and rigidly secured to the front and rear transverse members of the main supporting frame 1 of the machine. The tongue is also provided with oblique braces 21, the outer ends of which are rigidly secured to the tongue by means of the bolts 22, and the inner ends of which are 110 pivotally secured by means of the bolts 23 between pairs of braces 24, the outer ends

of the braces being rigidly secured to the main supporting frame by means of the bolts 25, and the inner ends of the braces being secured to the tubular transverse member of the main frame by means of the bolts 26.

The main rectangular supporting frame is provided with a rearwardly extending frame rigid therewith and comprising the rearwardly extending side bars 27, the forward ends of which are secured between the said pairs of braces 24 respectively, of the main frame, by means of bolts 28. These side bars 27 extend in parallel directions from their forward ends rearwardly and upwardly, resting against the under surface of the transverse tubular member 2 to stiffen the frame structure, and at points a short distance behind and above the transverse members are connected to the tubular member 2 of the main frame by the segmental brackets as will be hereinafter described, and are turned downwardly and then inwardly converging to embrace at their rear ends a bearing 29 for the swinging yoke 30 carrying the follower wheel 31.

The steering of the machine is effected by means of a steering-lever or bar 32 which is provided at its ends with foot rests 33 which is mounted upon a pivot 34 carried between the yoke formed by the bars 35 and 36 and which are rigidly secured together by a bolt 37. The bar 35 is turned downwardly at its ends and rigidly secured to the crossbraces 38 and 39, the ends of which are rigidly secured to the side bars 27 of the supporting frame. The steering lever is provided with a forwardly extending steering arm 40 which is rigidly connected to the said steering lever at one end, and is held in position with respect to said steering lever by means of the braces 41, and the forward end of this arm is pivotally connected between the said links 11 which connect the free ends of the said axle 45 crank arms. An aperture 42 is provided, through links 11 and the bar 35, for the reception of a pin 43 whereby the steering mechanism may be held in locked position.

A seat 44 is supported on a spring 45 which is secured to a brace 46, rigid with the frame of the machine, and also to the said bar 35 which supports the steering lever. The portion of the bar 35 supporting the steering lever is inclined to the frame of the machine and is substantially in a plane intersecting the seat whereby the steering lever is caused to swing substantially in a plane with the seat, making the steering lever easy to operate from the seat as the force applied from the seat is in the direction of the motion of the lever and not oblique to the plane of the movement of the lever as in other structures.

The tool carrying frame, or member, comprises three parallel tool bars 47, 48 and 49,

of channel iron, arranged in a vertical series extending transversely of the machine, supported in vertical slotted plates 50. The central bar 48 is fixed in position with respect to the said plates by means of pins 51, and is provided upon one side thereof, with a curved extension 52 forming a segmental rack 53. Pivoted to the lower portion of the extension 52, is the hand lever 54 carrying a spring pressed pawl 55, engaging said rack 53, and actuated by a handle 56. The top and bottom tool bars 47 and 49 are connected to the lever 54 by arms 57 secured in the channels of the bars and having curved outer ends connected to the levers by pivots 58 whereby, when the hand lever 54 is swung upon its pivot, the tool bars 47 and 49 are reciprocated transversely of the machine.

Improved tool clamps 59 are provided for the purpose of rigidly securing the shanks 60 of the tools 61 upon the said tool bars. Each of these clamps is constructed as shown in Figs. 8 and 9, and comprises a yoke 62 having a rectangular inner portion adapted to fit over the tool bar and having outwardly diverging ends 63 provided with slots 64. A key 65 provided with a recess 66 in the outer edge thereof having inwardly converging sides 67 spaced to engage against the outer surfaces of the yoke, rests in the slots and between the outer ends of the yoke and the tool shank 60. The inner end of the yoke is provided with a set screw 68 adapted to engage against one side of the tool bar, and to draw the yoke inwardly with respect to its wedge, whereby the sides of the yoke are forced against the sides of the tool bar by the converging sides of the recess in the wedge and the tool shank is held rigidly in place.

The tool frame is pivotally secured to the main supporting frame of the machine by means of the arms 69, the rear ends of which are rigidly secured to the supporting plates 50 by rivets 70, and the forward ends of which are pivoted between the side members of the main frame 1 and the brackets 71, rigid with the same upon the bolts 72. For swinging the tool frame, a pair of hand levers, or actuating members, 73, are provided, arranged one upon each side of the seat and substantially in vertical alinement with the forward ends of the side bars 27 of the rear portion of the frame of the cultivator. The forward ends of these levers 73 are pivoted by means of bolts 74 upon brackets 75, which are rigidly secured to the tubular member 2 of the main frame by the bolts 26 which pass through open ended slots 76 in the cylindrical portions of the brackets, and as heretofore described, also pass through the tubular member and the inner ends of the frame braces 24 to which the tongue and the side bars 27 of the rear portion of the frame are connected. The brackets 75 are also

rigidly secured to the outer sides of the said side bars 27 of the frame by means of bolts 77 which pass through the outer lower ends of the brackets and the portions of the side bars at the vertex of the angle between the upwardly and the downwardly extending portions thereof. Extending downwardly from the brackets, are arms 78 integral therewith, which bear against the outer side surfaces of the downwardly extending forward portions of the said side bars 27 of the frame to further brace the frame and bracket. The curved portion of the bracket is provided with slots 79, and the levers 73 are provided with the usual spring engaged pawl 80' engaging said slots. The hand levers 73 are each separately connected to the tool frame by means of a well-known form of yielding telescoping connection 80, and the vertical position and movement of the tool frames is thus controlled from the seat of the cultivator by means of the hand levers 73 which may be operated either separately, or in unison. Furthermore, the tongue 18 of the cultivator, is yieldingly supported by the hand levers, by means of a spiral spring 81, which is secured at one end to the inner end of the tongue and at its opposite end to a slightly flexible cross bar 82, the ends of which are rigidly secured by bolts 83 to the inner portions of the hand levers. With this construction in mind, it is evident that when the levers 73 are operated to raise the tool frame, the weight of the tongue acting through the spiral spring 81 assists in the operation; and, moreover, the weight of the tongue is ordinarily fully sustained by the spring, thus relieving the necks of the draft animals of the burden, preventing sores.

Although I have shown only the preferred form in which this invention may be embodied, I do not limit myself to this particular construction, as it is evident that many changes might be made in the construction shown, without departing from the spirit of this invention or the scope of the appended claims.

Having thus fully described my invention, what I claim and desire to protect by Letters Patent of the United States is:

1. In a cultivator, the combination with a supporting frame, of a draft member pivotally connected with said frame, a tool frame pivotally connected with said supporting frame, and an actuating lever connected to support said draft member and pivotally connected to shift said tool frame into and out of operative position, said tool frame being counterbalanced by said draft member.

2. In a cultivator, the combination with a supporting frame, of a draft member pivotally connected with said frame, a tool frame pivotally connected with said supporting frame, an actuating lever connected to shift

said tool frame into and out of operative position, and a flexible connector between said lever and said draft member forward of its pivot, supporting the latter and arranged to counterbalance said tool frame by said draft member. 70

3. In a cultivator, the combination with a supporting frame, of a draft member, a tool carrying member and an actuating member each independently pivoted to said frame, a yielding connection between said actuating member and said draft member, and a yielding connection between said actuating member and said tool carrying member. 75

4. In a cultivator, the combination with a supporting frame, of an L-shaped axle pivoted to said frame upon each side thereof, a wheel carried by each axle, a crank arm rigid with each axle, a seat mounted upon said frame, a steering bar extending transversely of said frame and having a foot rest at each end thereof pivoted to said frame to swing substantially in a plane intersecting the said seat, a steering arm rigid with said bar, extending longitudinally of said frame, and a bar connecting the free ends of said crank arms to the free end of said steering arm. 80 90

5. In a cultivator, the combination with a supporting frame, of a draft member pivoted thereto to swing vertically, a pair of independently movable levers each pivoted to said frame to swing vertically, yielding means connecting said levers and connecting said levers to said draft member, means to lock each of said levers in a fixed position, a tool carrying member pivoted to said frame to swing vertically independent of said draft member, and means connecting 100 105 said tool carrying member to said levers.

6. In a cultivator, the combination with a supporting frame, of a draft member pivoted thereto to swing vertically, a pair of independently movable levers each pivoted to said frame to swing vertically, a connection between said levers and a yielding connection between said first mentioned connection and said tongue, means to lock each of said levers in a fixed position, a tool carrying 110 115 bar pivoted to said frame, to swing vertically, and yielding connections between said bar and said levers.

7. In a cultivator, the combination with a supporting frame, of a draft member pivoted thereto, a pair of independently movable actuating members connected to said supporting frame, a seat between said actuating members, and means connecting said draft member and said actuating members. 120 125

8. In a cultivator, the combination with a frame, of a tongue pivoted thereto, a seat on said frame, a pair of independently movable levers pivoted to said frame upon opposite sides of said seat respectively, a cross 130

bar connecting said levers, and yielding means connecting said cross-bar to said tongue.

9. In a cultivator, the combination with a frame, of a draft member connected thereto, a tool carrying member and an actuating member each independently and movably connected to said frame, a connection between said actuating member and said draft member, and a connection between said actuating member and said tool carrying member.

10. In a cultivator, the combination with a supporting frame, of a draft member, a tool carrying member and an actuating member each movably connected to said frame, a yielding connection between said actuating member and said draft member, and a yielding connection between said actuating member and said tool carrying member.

11. In a cultivator, a main frame comprising two transverse bars spaced longitudinally of the cultivator, a pair of braces for supporting a traction member, each of said braces being connected at one end to one of said bars, and at its other end to the other of said bars, a traction member pivoted between said braces upon each side of said first mentioned braces, one end of each of said side braces being connected to one of said transverse bars and the other end of each side brace being connected to the other of said bars, and a rearwardly extending side bar secured between each of said pairs of side braces.

12. In a cultivator, a main frame comprising two transverse bars, a pair of braces extending longitudinally of the cultivator between said bars, a side bar having its forward end secured between said pair of braces and extending rearwardly beneath one of said transverse bars, a slotted bracket secured to said last mentioned transverse bar and to said side bar, a tool carrying member movable with respect to said frame, and means engaging said bracket for actuating said tool carrying member.

13. In a cultivator, the combination with a frame comprising two transverse bars, of a brace between said bars, a slotted bracket upon one of said bars, a bolt through said bracket and through said brace to hold the same in position, and an actuating hand lever pivoted to said bracket.

14. In a cultivator, the combination with a frame, of wheels mounted to swing on independent vertical axes, a seat mounted on said frame, a pair of foot rests mounted to swing substantially in a plane intersecting said seat, and means actuated by said foot rests arranged to steer the cultivator by swinging said wheels upon said axes.

15. In a cultivator, a main supporting frame extending substantially the full width of the machine, and having a transverse

member forming the rear side thereof, a rearwardly extending frame including a bar secured to said main frame forwardly of said transverse bar and extending rearwardly beneath said transverse bar contacting against the under side thereof, and a segmental bracket secured to said transverse bar extending rearwardly therefrom and connected to said rearwardly extending bar in the rear of said transverse bar.

16. In a cultivator, a substantially rectangular main supporting frame extending substantially the full width of the machine, braces between and connected to the front and rear sides of said main frame, a draft member connected to said braces and extending forwardly from said frame, and a frame secured to said braces and extending rearwardly of said main frame.

17. In a cultivator, a main frame comprising a transverse bar, a side bar having its forward end secured to said main frame in front of said transverse bar and extending rearwardly beneath said transverse bar, a slotted bracket secured to said transverse bar and to said side bar, a tool carrying member movable with respect to said frame, and means engaging said bracket for actuating said tool carrying member.

18. In a cultivator, a main frame comprising a transverse bar, a brace secured to said main frame and extending longitudinally thereof, a slotted bracket secured to said transverse bar and to said brace, a tool carrying member movable with respect to said frame, and means engaging said bracket for actuating said tool carrying member.

19. In a cultivator, a main frame comprising a transverse bar, a brace secured to said main frame and extending longitudinally thereof, a slotted bracket secured to said transverse bar and to said brace, a tool carrying member movable with respect to said frame, a lever pivoted to said bracket, and a pawl carried by said lever.

20. In a cultivator, the combination with a frame, of a draft member movably connected thereto, a seat on said frame, a pair of independently movable actuating members movably connected to said frame upon opposite sides of said seat respectively, means connecting said actuating members, and a connection between said means and said draft member.

21. In a cultivator, the combination with a supporting frame, of an actuating lever pivoted thereto, a tool carrying member movably connected to said frame, a yielding connection between said actuating lever and said tool carrying member, and a yielding connection between said actuating member and said frame.

22. In a cultivator, the combination with a frame, of a draft member, a tool carrying member and an actuating member, each in-

dependently movable with respect to said frame, a connection between said actuating member and said draft member, and a yielding connection between said actuating member and said tool carrying member said draft member and said tool carrying member each being moved with respect to said frame by the movement of said actuating member with respect to said frame.

23. In a cultivator, the combination with a rigid supporting frame, of a tongue pivoted thereto extending forwardly therefrom, a hand lever pivoted to said frame, and a spring connected at one end to said lever and at its other end to said tongue between the free front end of said tongue and its pivot, and arranged to support said tongue.

24. In a cultivator, a main frame comprising two transverse bars, a pair of braces extending longitudinally of the cultivator between said bars, a side bar having its forward end secured between said pair of braces and extending rearwardly beneath and in contact with one of said transverse bars, a slotted bracket secured to said last mentioned bar and to said side bar, a tool carrying member pivoted to said frame, and a lever pivoted to said bracket and having a pawl adapted to engage the slots of said bracket for actuating said tool carrying member.

25. In a cultivator, a substantially rectangular main supporting frame extending substantially the full width of the machine, braces between the front and rear sides of said main frame, a draft member pivoted to said braces and extending forwardly from said frame, and a frame secured to said braces and extending rearwardly of said main frame.

26. In a cultivator, the combination with a frame comprising a transverse cylindrical bar, of a transverse flat bar parallel thereto and in front thereof, a slotted bracket depending from said cylindrical bar and adjustable longitudinally thereof, a carrying wheel supported by said bracket, and a cross brace between the lower end of said bracket and said flat transverse bar, said transverse bar being provided with spaced holes for the adjustment of said brace.

27. In a cultivator, the combination with a supporting frame, of a draft member pivoted thereto, a pair of independently movable actuating members connected to said supporting frame, a seat between said actuating members, a yielding connection between said draft member and said actuating members, and a tool carrying member pivoted to said frame and connected to said actuating member.

28. In a cultivator, the combination with a frame, of a draft member mounted to oscillate thereon, a seat upon said frame, a pair of actuating members movably connected to said frame and arranged upon opposite sides respectively of said seat, means connecting said actuating members to said draft member, and a tool carrying member pivoted to said frame and connected to said actuating members.

29. In a cultivator, a main frame comprising two transverse bars spaced longitudinally of the cultivator, a brace secured at one end to one of said bars and at its other end to the other of said bars, a bar having one end secured to said brace, said bar extending longitudinally of the cultivator and being in contact with one of said transverse bars, a slotted bracket secured to said last mentioned transverse bar and to said longitudinal bar, a tool carrying member pivoted to said frame, and means engaging said bracket for actuating said tool carrying member.

30. The combination with a supporting frame, of an L-shaped axle pivoted to said frame upon each side thereof, a wheel carried by each axle, a crank arm rigid with each axle, a steering bar pivoted to said frame, a steering arm rigid with said bar, and links connecting the free ends of said crank arms to the free end of said steering arm.

In witness whereof I have hereunto set my hand this eighth day of January, A. D. 1908.

SAMUEL L. ALLEN.

Corrections in Letters Patent No. 1,008,445.

It is hereby certified that in Letters Patent No. 1,008,445, granted November 14, 1911, upon the application of Samuel L. Allen, of Moorestown, New Jersey, for an improvement in "Cultivators," errors appear in the printed specification requiring correction as follows: Page 2, line 29, after the reference-numeral "33" the word "and" should be inserted; line 31, after the reference-numeral "36" the word "and" should be stricken out, and line 58, for the word "with" read *intersecting*; page 3, line 114, for the word "tongue" read *draft member*; page 4, line 58, after the word "mounted" insert the words *upon an upwardly extending axis*, and lines 126-127, for the word "member" read *lever*; page 5, line 5, after the word "member" insert a comma; and that the said Letters Patent should be read with these corrections therein that the same may conform to the record of the case in the Patent Office.

Signed and sealed this 19th day of December, A. D., 1911.

[SEAL.]

E. B. MOORE,
Commissioner of Patents.
